UNITED STATES PATENT OFFICE.

MARTIN HEMLEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

SEWING-MACHINE BOBBIN-CASE LATCH.

Application filed March 26, 1924. Serial No. 701,895.

This invention relates to sewing machine bobbin-cases and has for an object to provide such a bobbin-case with a latch which securely holds the bobbin in place and is securely held in operative position, yet in case of damage may be readily removed from the bobbin-case for repair or replacement.

Further objects of the invention will appear from the following description and 10 claim.

To the attainment of the ends in view, a bobbin-case having a central arbor is removably fitted with a latch supporting element on which the bobbin-latch-lever is pivotally 15 mounted. The latch-lever, when in a closed position, extends radially across the rearward or open end face of the bobbin-case and has its bent free end received in a notch in the side wall or rim of the bobbin-case. The 20 latch may be swung 90° about its pivot to a position in line with the central arbor for removal of the bobbin. The latch-supporting shank may house a spring and pressure head adapted to bear against side and end faces 25 provided at the pivoted end of the latch-lever to resiliently hold the latter in either closed or open position, respectively.

In the accompanying drawings, Figs. 1 and 2 are, respectively, front and rear face views 30 of a bobbin-case embodying the invention. Fig. 3 is a section on the line 3—3, Fig. 2. Fig. 4 is a perspective view of the bobbin-case from which the latch has been removed. Fig. 5 is a perspective view of the removed latch 35 and Fig. 6 is a disassembled perspective view of the latch.

The invention is illustrated as embodied in a bobbin-case of the type disclosed in my co-pending application Serial No. 651,800, filed 40 July 16, 1923. Such a bobbin-case has a cup-shaped body with a cylindrical wall or shell

1 and a web 2 extending diametrically across its outer face and supporting the centrally disposed arbor 3 for the bobbin 4. According to the present improvement, the arbor 3 45 is fixedly secured to the web 2 and is open at both its rear end 5 and its front end 6. Removably and telescopically fitted to the arbor 3 is the tubular shank 7, the front end-portion of which is split longitudinally at 50 9—9 and is fitted with the taper-headed expansion screw 10 which, as shown in Figs. 1 and 3, is accessible at the front face of the bobbin-case for manipulation to expand the front end of the shank 7 into secure gripping 55 engagement with the tubular arbor 3.

The removable shank 7 carries the bobbin-retaining means or latch which may comprise a latch-lever 11, pivoted on the pin 12 in the head 13 on the rear end of the shank 7. A 60 spring 14 and pressure head 15 are housed within the shank 7 and are adapted to bear upon one or the other of the angularly related faces 16, 17, to resiliently hold the latch-lever in closed or open position. The latch-lever is disposed at the open end of the bobbin-case and its free end 18 is bent over and fitted to a notch 19 in the side wall of the bobbin-case.

Having thus set forth the nature of the 70 invention, what I claim herein is:—

A bobbin-case having a cup-shaped body and a central fixed arbor, a latch-lever supporting element, means for detachably and fixedly securing said element to said arbor, 75 and a bobbin-latch pivotally mounted on said supporting element and disposed at the open end of said bobbin-case.

In testimony whereof, I have signed my name to this specification.

MARTIN HEMLEB.
